UNITED STATES PATENT OFFICE.

JOHN A. MURPHY, OF ST. LOUIS, MISSOURI, ASSIGNOR TO SCULLIN STEEL CO., OF ST. LOUIS, MISSOURI, A CORPORATION OF MISSOURI.

REVERSING-VALVE MECHANISM.

Application filed July 3, 1922. Serial No. 572,358.

To all whom it may concern:

Be it known that I, JOHN A. MURPHY, a citizen of the United States, residing at St. Louis, in the county of St. Louis and 5 State of Missouri, have invented certain new and useful Improvements in Reversing-Valve Mechanism, of which the following is a specification.

This invention relates to a new and improved reversing valve mechanism and more particularly to a mechanism for operating reversing valves of the type in use with open hearth furnaces and the like.

The air and gas systems of such furnaces 15 as generally constructed comprise passageways terminating in three adjacent openings. The movable reversing valve member comprises a hood adapted to form a connection between the center of the three openings and either 20 one or the other of the laterally spaced openings.

In order to provide a gas tight seal, it is customary to surround the three openings by a water-containing pan or tank; the lower 25 edge of the hood being submerged below the surface of the water. The reversing movement of these valves requires an upward lift so that the edge of the hood may be lifted from the water to clear the rims of 30 the openings and further requires a horizontal movement to bring the hood in registration with the desired openings. This composite movement has been accomplished heretofore either by rock arms or by supporting the hood upon rollers running upon 35 a track having elevations and depressions formed therein. In either case, no direct lift is given, but the upward movement is given simultaneously with a portion of the horizontal movement. Valve hoods moving 40 in this manner require that the rims surrounding the openings be relatively low in order that they may be cleared by the hood. These rims are subjected to the wear of 45 the flow of hot gases and are eroded comparatively rapidly. Where the rims are low, replacement of the entire rim casting is necessary at short intervals.

It is an object of the present invention to 50 provide an operating mechanism for valves of this type adapted to lift the valve vertically before giving it the required horizontal movement.

It is a further object to so co-ordinate the

means accomplishing the two movements 55 that the horizontal movement will automatically take place when proper vertical clearance is accomplished.

It is also an object to provide a mechanism of this character which is simple in construction and operation and adapted for 60 commercial application at relatively low cost.

Other and further objects will appear as 65 the description proceeds.

My invention comprises the use of separate actuating means, one means moving the hood vertically and the other means moving it horizontally. In the preferred form, 70 these means consist of cylinders containing pistons operated by fluid pressure. Preferably, the cylinders are so connected that fluid under pressure passes from the vertical cylinder to the horizontal cylinder when the piston in the vertical cylinder has reached 75 a predetermined height. Means are provided for selectively directing the fluid passing to the horizontal cylinder upon either side of the piston therein.

I have illustrated a preferred embodiment 80 of my invention in the accompanying drawings, in which—

Figure 1 is an elevation showing a valve equipped with my operating mechanism; 85 and

Figure 2 is a view of Figure 1 as seen from the left, certain parts being shown in section.

The passageways 5, 6 and 7 serve to carry the air or gas. The casting 8 is located above the openings of these passageways and is 90 provided with an outer rim 9 and inner rims 10, 11 and 12 surrounding the openings from passageways 5, 6 and 7, respectively. The casting thus forms a trough adapted to contain water, the water entirely surrounding the 95 three openings. The fixed cover 13 is provided with suitable doors 18 and 19 for inspection and cleaning purposes. The cover 13 encloses the valve hood 14 which latter is supported by plate 15 connected to piston rod 16 by pin 17. The plate 15 moves in a longitudinal slot 20 in the top of the cover member 13. The piston rod 16 is connected to a piston operating in the vertical cylinder 100 21.

This cylinder 21 is supported from carriage 22, the carriage being provided with rollers 23 which bear upon the lower flange

of the I-beam track 24. The track 24 is supported upon suitable framing 25. The vertical cylinder 21 is connected by yoke 26 to the piston rod 27, which piston rod is connected to a piston moving in the horizontal cylinder 28. The horizontal cylinder 28 is suspended by brackets 29 from the I-beam 24.

Referring now particularly to Figure 2, 10 the inlet passage 30 leads from any suitable source of compressed air or other fluid (not shown) to the valve 31. The valve 31 is operated by lever 32 pivoted at point 33. This lever 32 is connected by chains 34 and 35 to 15 the corresponding ends of the lever 36 whereby the two levers are caused to move together. This lever 36 is pivoted at 37 and operates valve 38. The operating handle 39 is connected to one end of the 20 lever 36.

The pipes 40 and 41 lead from valve 31, these pipes joining at 42 to form pipe 43 which pipe is connected by flexible hose coupling 44 to inlet 45 upon the lower portion 25 of the vertical cylinder 21. The valve 31 also connects the exhaust pipe 46. The outlet connection 47 upon the upper portion of the vertical cylinder 21 is connected by flexible hose 48 to the pipe 49 which 30 latter leads to valve 38. The pipe 50 connects one opening of the valve 38 with the right-hand end of the horizontal cylinder 28. The pipe 51 connects another opening of the 35 vertical cylinder and the valve 38 also connects with the exhaust pipe 52.

The hood being in the right-hand position as shown in Figure 1, the shift to the left-hand position will be accomplished by 40 thrusting down upon the lever operating handle 39. This thrust will be transmitted by chains 34 and 35 and both levers 32 and 36 will swing in a clockwise direction about their pivots.

45 Valve 31 is operated to connect the air inlet pipe 30 to the pipe 40 and the compressed air flows through pipe 43 and hose 44 to the underside of the piston in the vertical cylinder 21. When this piston rises to clear the port 47, the air passes through hose 48 and pipe 49 to the valve 38. The valve 38 has been moved to connect the pipe 49 to the pipe 50, and the compressed air flows through the pipe 50 to the horizontal 50 cylinder 28 where it thrusts against the piston and moves the vertical cylinder 21 and the depending valve hood laterally as far as the dotted line position of Figure 1.

When the hood has reached this position, 60 the handle 39 is brought back to neutral which serves to close off the air inlet passage 30 and to connect the pipe 40 with exhaust pipe 46 and the pipe 50 with the exhaust pipe 52. The weight of the valve exhausts 65 the air from the vertical cylinder and the

valve is lowered into position, its lower edge being below the water lever in the casting 8.

Upon again reversing the furnace, the valve hood 14 is brought back to its original position by pulling upwardly upon the handle 39. This results in rotating the levers 32 and 36 in the counterclockwise direction. This movement of the valve levers serves to connect the air inlet 30 with the pipe 41 and compressed air again passes through pipe 43 and hose 44 to the underside of the piston in the vertical cylinder 28.

When the piston clears the port 47, the compressed air again passes through hose 48 and pipe 49 to the valve 38. This valve 38 is now positioned so that air from pipe 49 passes through pipe 51 to the left-hand end of the horizontal cylinder 28 and thrusts against the piston therein to move the vertical cylinder and depending valve back laterally as far as the full line position of Figure 1. When the valve reaches this position, the handle 39 is lowered to neutral and the passage 41 is connected by valve 31 90 to the exhaust passage 46 and the hood 14 is lowered into place. Simultaneously, pipe 51 is connected to exhaust passage 52 by valve 38 and the pressure is relieved in that cylinder. 95

My valve operating mechanism is thus put in motion in either direction by a single movement of an operating handle. The connections are such that horizontal movement takes place automatically upon completion of the proper vertical movement and cannot take place until such vertical movement is accomplished. This method of moving the valve permits the use of relatively high rims around the gas openings 100 which rims consequently withstand wear for a relatively long period and avoid the necessity for frequent renewal of the rim casting. 105

It is to be understood that the particular form shown is illustrative only and I reserve the right to make such modifications as come within the scope of the appended claims. 110

I claim:

1. Reversing valve mechanism comprising 115 a valve hood, means for moving said hood vertically and a second means adapted to move it horizontally, said means being interconnected whereby the second means becomes operative upon a predetermined lifting movement by the first means. 120

2. Reversing valve mechanism comprising 125 a valve hood, a fluid operated piston adapted to move said hood vertically, a second fluid operated piston adapted to move said hood horizontally, and interconnected operating means for said pistons whereby the horizontally acting piston becomes operative upon a predetermined movement by the vertically operating piston. 130

3. Reversing valve mechanism comprising a valve hood, a cylinder having a fluid operated piston therein adapted to move said hood vertically, a second cylinder having a fluid operated piston adapted to move the hood horizontally, means for supplying fluid under pressure to said vertical cylinder, and means for automatically supplying fluid under pressure to said horizontal cylinder upon a predetermined movement of said vertical piston.

4. Reversing valve mechanism comprising a valve hood, a cylinder having a fluid operated piston therein adapted to move said hood vertically, a second cylinder having a fluid operated piston adapted to move the hood horizontally, means for supplying fluid under pressure to said vertical cylinder, and means for automatically passing said fluid under pressure from the vertical cylinder to said horizontal cylinder upon a predetermined movement of said vertical piston.

5. Reversing valve mechanism comprising a valve hood, a cylinder having a fluid oper-

ated piston therein adapted to move said hood vertically, a second cylinder having a fluid operated piston adapted to move the hood horizontally, means for supplying fluid under pressure to said vertical cylinder and means for selectively passing the fluid under pressure from the vertical cylinder to either side of the piston in the horizontal cylinder.

6. Reversing valve mechanism comprising a valve hood, a cylinder having a fluid operated piston therein adapted to move said hood vertically, a second cylinder having a fluid operated piston adapted to move the hood horizontally, means for supplying fluid under pressure to said vertical cylinder and means for selectively passing the fluid under pressure from the vertical cylinder to either side of the piston in the horizontal cylinder automatically upon a predetermined movement of the vertical piston.

Signed at St. Louis, Missouri, this 16th day of June, 1922.

JOHN A. MURPHY.
